United States Patent Office

Des. 214,994

Patented Aug. 19, 1969

214,994

JAR

Lawrence Goldman, Valley Stream, N.Y., assignor to
General Mills, Inc., a corporation of Delaware

Filed May 3, 1968, Ser. No. 11,778

Term of patent 14 years

Int. Cl. D9—01

U.S. Cl. D9—129

FIG. 2

FIG. 5

FIG. 1

FIG. 3

FIG. 4

FIG. 6

FIGURE 1 is a plan view of a jar showing my new design;

FIGURE 2 is a top view thereof;

FIGURE 3 is a right side view thereof;

FIGURE 4 is a bottom view thereof;

FIGURE 5 is a cross sectional view thereof taken along line 5—5 of FIGURE 1; and

FIGURE 6 is a cross sectional view thereof taken along line 6—6 of FIGURE 1.

The dominant features of my design reside in the portions shown in full lines.

I claim:

The ornamental design for a jar, substantially as shown and described.
